CLAIM

The ornamental design for a telescopic rod, as shown and described.

DESCRIPTION

FIG. 1 is a perspective view of the telescopic rod showing my new design;

FIG. 2 is a front view thereof;

FIG. 3 is a rear view thereof;

FIG. 4 is a left view thereof;

FIG. 5 is a right view thereof;

FIG. 6 is a top view thereof; and

FIG. 7 is a bottom view thereof; and,

FIG. 8 is an enlarged perspective view thereof.

The dashed lines shown in FIGS. 1-8 are the purpose of illustrating unclaimed subject matter only and form no part of the claimed design. The dot-dash lines in FIGS. 1-5, and 8 represent unclaimed boundary lines of the claimed design.

1 Claim, 5 Drawing Sheets
